(57) **CLAIM**

The ornamental design for a display screen or portion thereof with graphical user interface, as shown and described.

DESCRIPTION

The contents of U.S. application Ser. No. 29/450,071, filed Mar. 15, 2013, are incorporated herein in their entirety.

FIG. 1 depicts a front view of a display screen or portion thereof with graphical user interface showing the new design; and,

FIG. 2 depicts a second embodiment thereof.

The broken lines in the drawings represent the display screen or portion thereof and form no part of the claimed design.
